UNITED STATES PATENT OFFICE

2,464,909

CURTAIN HANGER

Graham B. Waddell, Pittsburgh, Pa.

Application May 7, 1946, Serial No. 667,837

5 Claims. (Cl. 248—263)

1

This invention relates to a curtain holder having for one of its objects to provide an improved curtain holder having means adapted to facilitate the placing thereon of a curtain and the removal of the same.

Another object of the invention is to provide a curtain holder of the single hanger type with means for converting same into a double hanger type without altering the lug member which supports the single hanger.

Still another object of the invention is to provide a curtain hanger with lug members, each adapted to serve as a support for a pair of L-shaped brackets to which are removably attached tubular curtain carriers, said pair of brackets independently and swivelly attached to one of said lug members.

Yet another object of the invention is to provide a curtain holder with means whereby the same may be transformed from a one hanger type to a two hanger type without altering the hanger supporting means.

Another object of the present invention is to provide an exceedingly simple and effective curtain holder which may be used for various widths of windows or doors.

A further object of the invention is to produce a simple and inexpensive device and yet one which will be exceedingly effective for the purpose for which it is designed.

Further objects of the present invention are to provide a device of the class set forth which is simple in its construction and arrangements, strong, durable and efficient in its use, readily installed, and inexpensive to manufacture.

To the accomplishment of these and such other objects as may hereafter appear the invention consists of the novel construction, combination and arrangement of parts herein specifically described and illustrated in the accompanying drawing, wherein is shown an embodiment of the invention, but it is to be understood that changes, variations and modifications may be resorted to which come within the scope of the claims hereunto appended.

In the drawing wherein like numerals of reference designate corresponding parts throughout the several views,

Figure 1 is a perspective view of a curtain hanger constructed in accordance with the present invention applied to a door or window frame, showing in dot and dash lines the L-shaped brackets in a downward position for readily removing therefrom or attaching thereon the tubular members which serve as a curtain carrier.

2

Figure 2 represents an enlarged, perspective assembly view of the L-shaped brackets as used for a two hanger type curtain holder showing the lug member fastened to a window frame and showing in dot and dash lines the position of the L-shaped brackets when the tubular members are removed therefrom.

Figure 3 is a top view of a double hanger type support secured to the frame of a window or door, partly in cross-section.

Figure 4 is a front view of Figure 3.

Figure 5 is a sectional view through a lug member as used in this invention.

Figure 6 is a front view of Figure 5.

Figure 7 is a plan view of the annular wire spring shown in Figure 5 which is intended to serve as a retaining means for one end of the L-shaped bracket.

Figure 8 is a perspective view of the assembled attachment parts which transform a single hanger type support into a double hanger type support.

In general, the present invention is concerned with an improvement of my application Serial No. 494,679, filed July 1943, which matured into Patent No. 2,355,489 on August 8, 1944.

In carrying out my invention as here embodied, 10 represents lug members fastened to the window casing 11. Each lug member comprises a tubular socket 12, terminating at one end thereof in a flanged disc 13. A central aperture 14 is provided in said disc 13 to receive a screw 15, by means of which said lug member 10 is fastened to a door or window frame, as best shown in Figure 3 of the drawing.

35 At this time it is desirable to mention that the lug members, as disclosed in my Patent No. 2,355,489, are shown provided with an internally threaded socket adapted for threaded engagement with the terminals of the L-shaped brackets.

40 The new improved design herewith disclosed eliminates these internally threaded lug members including the threaded terminals of the L-shaped brackets thereby attaining certain important features not possible in the patented construction.

45 One terminal of the L-shaped bracket 16, as shown in Figures 2, 3 and 4, is introduced into the tubular socket 12 of the lug member 10 and prevented from coming out of the socket by means of an annular wire spring member 17, such as shown detailed in Figure 7 of the drawings.

50 This spring member 17 is sprung into the annular groove 18, and when in final position, the

inside diameter thereof should be slightly smaller than the bore 19 of said tubular socket 12, so that when an end of said L-shaped bracket 16 is inserted into the bore 19, the spring member 17 will surround the exterior end portion of bracket 16 and exert a pressure against it thereby preventing same from coming out of the socket 12, but at the same time will permit to swivel freely in the socket 12.

As will be noted, the device may be used as a single hanger type curtain holder or a double type curtain holder, the latter being shown in Figures 1 to 4, inclusive.

The single hanger type curtain holder comprises a pair of lug members 10, a pair of L-shaped brackets 16 and a tubular member 36, while the double hanger type curtain holder consists in addition to the parts mentioned of the unit 20 which is illustrated in Figure 8 and shown assembled in Figures 1 to 4, inclusive.

The aforesaid unit 20 comprises an attachment link 21 having aligned apertures 22 and 23 in which the large aperture 22 is adapted to clear the exterior portion 24 of said socket 12 and a smaller aperture 23 is adapted to receive the reduced neck portion 25 of the L-shaped bracket 26 which neck portion is then riveted over link 21 by means of which said link 21 is securely held in aligned position with said bracket 26.

Between the shoulder 27 of said bracket 26 and the neck portion 25 is a shank portion 28 on which is swivelly mounted the locking link 29. The latter comprises a flat link-like member 30 having an aperture 31 and a substantially semi-circular opening 34.

In position, this locking link 29 is mounted between the attachment link 21 and the terminal of the L-shaped bracket 26, so that the shank portion 28 thereof may be engaged by the aperture 31 of the locking link 29, thereby serving as a swiveling bearing. The L-shaped bracket 26 and the attachment link 21 are riveted together with the locking link 29 swivelly mounted therebetween.

When it is desired to use a double hanger type curtain holder, the unit 20 is attached to the single hanger type curtain holder as follows:

First, the free end 32 of the L-shaped bracket 16 is introduced into the aperture 22 of the attachment link 21 until the latter comes in abutment with the head of screw 15 inserted in aperture 14 of the flanged disc 13, as best shown in Figure 3 of the drawing, after which the locking link 29 is swung around until the semi-circular cut-out portion 34 engages the exterior groove 35 of the socket 12.

This operation will retain the said unit 20 against the flange 13 of the lug member 10, at the same time permitting it to freely swivel in the exterior groove 35 of socket 12 around the longitudinal axis of lug member 10, so that when the tubular members 36, which carry the curtains 37 are removed from the L-shaped members 16 and 26, these will assume a downward position, such as shown in dot and dash lines in Figure 2.

A complete double hanger consists of a pair of lug members 10, each fastened by a screw 15 to the window frame or casing 11 as shown in Figure 1. Each lug member supports the L-shaped brackets 16 and 26 in a manner set forth.

Preferably, one set of the L-shaped brackets 16 and 26 are provided with longer free ends, so that the tubular members 36 which carry the curtains 37 may be moved over the longer free ends when

it is desired to remove the tubular members, when replacing the curtains.

After the tubular members are removed, the brackets automatically assume a downward position as shown in dot and dash lines in Figure 1 to facilitate replacing of the tubular member while the person stands on the floor, after which the tubular member is swung towards the opposite lug member while the person goes up the ladder and inserts the tubular member into the free ends of said brackets.

It will be noted, that in view of the fact that the free ends of the L-shaped brackets, after the tubular members are removed therefrom, always assume a downward position, due to their pendulum like mounting permitting to swivel by the urge of gravity; in this position will facilitate removal or attachment of the tubular member to the brackets without requiring to move the ladder from one end of the other. This feature is considered one of the distinctive advantages of the present invention, it will also be understood that the structure of the several parts of the device may be varied to suit similar uses thereof, also the same may be produced in different sizes to correspond with the size of the windows or doors to which it is to be fitted.

A distinctive characteristic of my device is that bracket 16 as well as unit 20, carrying bracket 26, are swivelly mounted on lug member 10, the axis of oscillation of the former being the longitudinal axis of the latter. This axis coinciding with that of attachment screw 15 the loads on lug member 10 act substantially centrally securing maximum rigidity and carrying capacity of the device.

I claim:

1. A curtain holder comprising a pair of lug members, each comprising a tubular socket having at one end a flanged disc concentric therewith; the exterior of said tubular socket being adapted to rotatably carry an attachment link adjacent to said disc and being provided with an annular groove for rotatably engaging locking means for confining said attachment link axially between said disc and said groove, an L-shaped bracket, one leg of which is adapted to swivelly engage said tubular socket, the other end of which adapted to engage a curtain rod for sustaining a curtain; a single screw to secure each of said lug members, spaced apart, to a window casing, said screw concealed from sight.

2. A curtain holder comprising a pair of lug members, each comprising a tubular socket having at one end a flanged disc concentric therewith; an L-shaped bracket adapted to swivelly engage one leg thereof in said tubular socket, the other end being adapted to engage a curtain rod for sustaining a curtain; said flanged disc provided with a central aperture adapted to engage a screw for securing said lug members to a window frame and means to conceal said screw from sight.

3. A curtain holder comprising a pair of lug members, each provided with a tubular socket having at one end a flanged disc concentric therewith; the exterior of said tubular socket being adapted to rotatably carry an attachment link adjacent to said disc and being provided with an annular groove for rotatably engaging locking means for confining said attachment link axially between said disc and said groove, an L-shaped bracket, one leg of which is adapted to swivelly engage said tubular socket, the other leg of which adapted to engage a curtain rod for sustaining

a curtain; an attachment link provided with a second L-shaped bracket adapted to swivelly engage the exterior of said tubular socket; the free end of said second L-shaped bracket adapted to engage a second curtain rod for sustaining a second curtain, locking means for swivelly retaining said attachment link in position and a single screw to secure each of said lug members, spaced apart, to a casing, said screw concealed from sight.

4. A curtain holder according to claim 3 in which said locking means comprises a link swivelly mounted on said attachment link adapted to engage said annular groove.

5. A curtain holder according to claim 2 in 15 which said tubular socket rotatably mounts an

attachment link carrying a second L-shaped bracket whereby both said first L-shaped bracket and said attachment link are rotatable about the longitudinal axis of said tubular socket.
